UNITED STATES PATENT OFFICE.

EDWARD L. DOBBINS, OF JEWELL, KANSAS.

BUILDING-BLOCK.

1,019,228.

Specification of Letters Patent.

Patented Mar. 5, 1912.

Application filed February 14, 1908. Serial No. 415,933.

To all whom it may concern:

Be it known that I, EDWARD L. DOBBINS, a citizen of the United States, residing at Jewell city, in the county of Jewell, State 5 of Kansas, have invented certain new and useful Improvements in Building-Blocks; and I do hereby declare the following to be a full, clear, and exact description of the invention, such as will enable others skilled 10 in the art to which it appertains to make and use the same.

The present invention relates to improvements in cement building blocks, and more particularly to articles of that class designed especially for use in the construction 15 of chimneys, it being the general object of the invention to provide a series of such blocks adapted when mounted one upon another, to form a chimney which is to all in- 20 tents a single solid homogeneous structure.

To this end, the invention resides in the provision of a cement block comprising spaced inner and outer walls and a series of spaced members connecting the same and 25 cast or molded integral therewith, the upper and lower faces of said members being spaced from the corresponding edges of the walls so as to form cement receiving cavities between said walls which communicate 30 with the spaces between said members, thus permitting the cement to fill said cavities and spaces and form a monolithic lock between the superposed blocks.

The invention will be readily understood 35 from a consideration of the following detailed description, and its preferred embodiment is illustrated in the accompanying drawings, in which corresponding parts or features, as the case may be, are designated 40 by similar reference numerals in the several views.

Of the said drawings: Figure 1 is a perspective view of the improved block. Fig. 2 is a vertical section taken on the line 2—2 45 of Fig. 1. Fig. 3 is a vertical section taken on the line 3—3 of Fig. 1.

Referring more particularly to the drawings, the block illustrated therein is shown as comprising a rectangular inner wall 5 50 surrounded by and inclosed within a similarly-shaped outer wall 6, said walls being arranged in spaced relation to each other and connected together by corner pieces 7. The walls and corner-pieces form an in-

tegral structure which is cast, molded or 55 otherwise constructed as preferred.

The corner-pieces are L-shaped in horizontal cross section. The height of one wall is equal to that of the other wall, while the height of the corner-pieces is less than that 60 of the walls, as shown, the upper and lower faces of the corner-pieces being in consequence, spaced from the corresponding edges of the walls, the upper faces of the corner-pieces lying below the upper edges of the 65 walls, whose lower edges extend below those of the corner-pieces.

The open spaces 9 between the corner-pieces, as well as the open spaces or cavities 8 between the upper and lower faces of the 70 corner-pieces and the corresponding edges of the walls, are adapted to be filled by a binder 10 of plastic cement, as hereinafter described.

In the construction of the chimney, the 75 blocks are superposed one upon another, until the required height is reached; plastic cement is then poured through the openings 9, filling the same and the mating open spaces or cavities 8 between adjacent blocks. 80 The cement binder on setting thus forms a solid monolithic lock between the blocks, as will be apparent, the provision of the spaces or cavities 8 affording a materially increased area of contact for the cement with 85 the blocks and proportionately strengthening the joint between the same.

The space inclosed by the sides of the inner wall of the completed chimney forms a passage 11, for the products of combustion. 90

While the blocks are designed primarily for use in the construction of chimneys it is to be understood that they may be used with equal facility in the construction of culverts and drain pipes, in which latter 95 instance, the inner and outer walls of the block are in the form of concentric circles in cross section, as shown in Fig. 4.

What is claimed is:

1. A building block for chimneys comprising a unitary structure having an outer wall, an inner wall concentric with and spaced from the outer wall, said inner wall being of equal height to the outer wall and the terminal faces of said inner and outer 100 walls lying in the same plane, spacers between said inner and outer walls and spaced around the inner wall, the terminal faces 105

of said spacers being spaced from the adjacent terminal faces of the walls at equal distances, and the confronting faces of said walls being beveled continuously from the 5 planes of the terminal faces of the spacers.

2. A structure comprising a series of superposed building blocks each comprising a unitary structure having an outer wall, an inner wall concentric with and spaced 10 from the outer wall, said inner wall being of equal height to the outer wall and the terminal faces of said inner and outer walls lying in the same plane, spacers between said inner and outer walls and spaced around the 15 inner wall, the terminal faces of said spacers being spaced from the adjacent terminal faces of the walls at equal distances, and the

confronting faces of said walls being beveled continuously from the planes of the terminal faces of the spacers; in combination with a packing between the inner and outer walls of cementitious material, said packing completely filling the space between said walls whereby the filling is provided with a series of opposed pairs of inner and outer 20 25 circumscribing ribs constituting means to lock the blocks firmly together.

In testimony whereof, I affix my signature, in presence of two witnesses.

EDWARD L. DOBBINS.
